LYMAN R. ROBERTS, OF RUTHERFORD, NEW JERSEY, ASSIGNOR TO UNDERWOOD TYPE-WRITER COMPANY, OF NEW YORK, N. Y., A CORPORATION OF DELAWARE.

TYPE-WRITING MACHINE.

1,220,892.

Specification of Letters Patent. Patented Mar. 27, 1917.

Application filed December 6, 1913. Serial No. 804,957.

To all whom it may concern:

Be it known that I, LYMAN R. ROBERTS, a citizen of the United States, residing in Rutherford, in the county of Bergen and 5 State of New Jersey, have invented certain new and useful Improvements in Type-Writing Machines, of which the following is a specification.

My invention relates to type-bar actions 10 for type-writing machines, and is an improvement upon the invention disclosed in my co-pending application No. 799,845, filed November 8, 1913. In said application the type-bar is provided with a slot in which 15 works a pin on an actuating lever, the slot being open at one end to permit the actuating lever to be releasably connected to the type-bar.

In the present application the slot in the 20 type-bar is closed at both ends, thereby materially strengthening the type-bar; and in order to permit the pin on the actuating lever to be disconnectably inserted in the slot in assembling the parts, said slot at its 25 upper end is enlarged sufficiently to receive the head of the connecting pin, said enlargement located beyond the normal path of travel of the pin in the slot. The type-bar may be readily removed by swinging it to 30 an intermediate position, lifting it off its fulcrum rod and then sliding it downwardly to bring said enlargement of the slot opposite the head of the connecting pin.

A locking surface at the end of the slot 35 is constructed to engage the actuating pin and prevent the type bar from swinging upward independently of pressure on the key, thus preventing rebound of the type-bars, and consequent interference or piling 40 up of the keys. A stop on the type bar segment limits the movement of the bar on its fulcrum, the elasticity of the bar permitting the type to be carried by momentum up to the platen. A more uniform and less violent 45 action of the types is thus obtained, the types are prevented from vibrating on the platen, and double printing or blurring is avoided.

In the accompanying drawings, 50 Figure 1 is a part sectional elevation view of a type-action embodying my invention,

the parts being in their normal positions of rest.

Fig. 2 is a similar view showing the position of the parts when the key is depressed. 55

Fig. 3 is an elevation view of the type-bar segment.

Fig. 4 is an enlarged detail view showing the means for connecting and disconnecting the type-bar to and from its actuating lever. 60

Figs. 5 and 6 illustrate the method of assembling the type-bar. Fig. 5 shows the position of the type-bar as it is placed on the connecting pin. Fig. 6 shows the type-bar as it is being placed on its fulcrum rod. 65

Horizontally-disposed key levers 1 are fulcrumed at their rear ends on a rod 2 and provided at their forward ends with finger-pieces 3. Each key lever has a slot-and-pin connection 4 with a bell-crank lever 5 pivoted 70 on a rod 6 and provided with a pin 7 working in a slot 8 formed in the shank of the type-bar 9. The type-bars are fulcrumed on a rod 10 mounted on a type-bar segment 11, the type-bars being positioned in radially- 75 arranged slots 12 in the segment.

When the key is depressed, the bell-crank lever 5 which forms an actuator or driving arm for the type-bar, is rotated and the pin 7 swings the type-bar about its fulcrum 10 80 from a horizontal or inclined position (Fig. 1) upwardly and rearwardly to a substantially vertical position in front of the platen 13. During this movement of the type bar, the pin 7 has a continuous movement along 85 the slot 8. The lower end of the slot 8 is only slightly inclined to the direction of movement of the pin 7, so that the initial movement of the type-bar relatively to that of the key lever is comparatively slow. As 90 the type-bar moves upward, the inclination of the slot 8 to the direction of movement of the pin 7 gradually increases, resulting in an increase in the relative speed of the type-bar. During the final portion of the 95 type-stroke, the relation of the parts is such that a high speed of the type-bar is obtained.

The operation during the pivotal movement of the type-bar about its fulcrum 10 is substantially the same as that fully set 100 forth in my co-pending application above referred to and need not be further de-

scribed here. In the present case, however, the pin 7 is not brought to the upper end of the slot 8 at the completion of the type stroke, and the movement of the type-bar 5 about its fulcrum 10 is limited by a rib 14 on the segment 11, which forms a stop for the type-bars when the type are a short distance from the printing point, the resiliency of the type-bar permitting the type to complete their strokes by momentum, as indicated by dotted lines in Fig. 2.

The lower end of the slot 8 is provided with a curved surface 15 transverse to a line joining the pin 7 with fulcrum 6, thus forming a lock for the type-bars to prevent them from rebounding. Interference or piling up of the type-bars in rapid writing, owing to a rebounding type-bar colliding with an adjacent type-bar, is thereby prevented.

20 The pin 7 is provided with a head 16 of greater diameter than the width of the slot 8 to prevent accidental separation of the type-bar and its actuator 5, the neck 17 of the pin working freely in the slot, but of sufficient width to prevent any material lateral play of the pin in the slot. The slot 8 is inclosed or completely surrounded by the type-bar so that the type-bar is not materially weakened by the slot.

30 To provide for assembling or removing the type-bar, an enlargement 18 is formed at the upper end of the slot 8 through which enlargement the head 16 can pass. The opening 18 is beyond the normal limit of movement of the pin 7 in the slot 8, as shown in Fig. 2.

The fulcrum rod 10 seats in a slot or recess 19 formed by a hook 20 and opening outward through a neck or passage 21. In assembling the type-bar, it is placed on the pin 7, the pin entering the slot at the opening 18 as shown in Fig. 5, and is then moved upwardly along the pin to the Fig. 6 position, to permit the fulcrum rod 10 to enter 40 the throat 21, and thus allow the type-bar to be hooked on to the rod 10. This operation is reversed in removing the type-bar, the latter being first swung up to an intermediate position and then lifted over the 45 fulcrum rod 10.

Variations may be resorted to within the scope of the invention, and portions of the improvements may be used without others.

Having thus described my invention, I 55 claim:

1. In a type-action, the combination of a type-bar having a hook, a fulcrum upon which the type-bar is detachably caught by means of said hook, a key lever, and an intervening actuator for the type-bar, the latter provided adjacent to said hook with a shank having a slot closed at both ends, and a headed pin on said actuator working in 60 said slot and movable continuously along the

slot during the type-stroke, said slot formed 65 with a locking surface at one end to lock the type-bar against rebound from its normal position of rest, and at its other end having an enlargement to permit the passage of the head of the pin for disconnecting the type 70 bar from the actuator.

2. In a type-action, the combination of a key lever, a type-bar provided with a closed transverse slot, and a driving arm operated by the key lever and comprising a headed pin having a continuous sliding movement in said slot throughout the printing stroke, said slot formed to gradually increase the speed of the type-bar relatively to that of the key lever throughout the printing 80 stroke, said slot having an enlargement at one end beyond the normal range of movement of said pin to permit the passage of the head of said pin for detachment, said type-bar having a separate open slot whereby it is detachably mounted on its pivot, said slots being so related that the type-bar detaches first at one slot and then at the other.

3. In a type-action, the combination of a type-bar formed with a slot entirely inclosed by the type-bar, and an actuator comprising a pin working in said slot and having a head of greater width than the slot, the slot formed with an enlargement through which said head can pass in connecting or disconnecting the parts, said enlargement located beyond the normal limit of travel of the pin in the slot during the type-stroke, said slot formed at the opposite limit of travel of said pin, with a locking surface 90 to lock the type-bar against rebound from its normal position of rest, and said type-bar also having an open-slot construction 95 for detachment from its pivot while said headed pin remains in its slot.

4. In a type-action, the combination of a pivoted type-bar, a key lever, and an interponent lever forming an actuator for the type-bar, the type-bar formed with a completely closed slot having an enlargement at 100 its upper end, and a locking surface at the lower end to prevent rebound of the type-bar, and a headed pin on said interponent lever working in said slot and removable from the type-bar at said enlargement, the type-bar also formed, near the upper end of said closed slot, with an open slot or recess forming a downwardly directed hook whereby the type-bar is detachably connected to its pivot.

5. The combination of a key-operated arm, a type-bar, and a fulcrum whereon said type-bar is pivoted, said type-bar formed with a hook whereby it is detachably caught upon said fulcrum, said type-bar having a shank extending past said hook, but separate therefrom, to permit the detachment of the type-bar from the fulcrum, said shank hav-

ing a slot extending transversely of the type-bar, and said driving arm having a headed pin working in said slot; said slot formed at its upper end with an enlargement to permit detachment of the type-bar from the headed pin, and so formed with relation to said hook as to permit the preliminary de-

tachment of the hook from the fulcrum while the headed pin is between the ends of the slot.
